UNITED STATES PATENT OFFICE

2,598,192

PROTECTIVE COVER FOR FRANGIBLE DISKS

Milton L. Poust, Riverside, Ill., assignor to Sears, Roebuck and Co., Chicago, Ill., a corporation of New York

Application August 16, 1948, Serial No. 44,468

2 Claims. (Cl. 206—46)

1

My invention relates to protective covers and is concerned more particularly with a cover intended primarily for protecting frangible grinding wheels and like elements in shipment.

Grinding wheels, which are ordinarily formed of carbide or similar frangible material, are ordinarily shipped in bulk, without separate wrappings, being thrown haphazardly into large boxes, barrels or other containers. Therefore, in the course of shipment, these wheels are frequently chipped at the edges and such articles, arriving at their destination in defective condition, must be sold at a reduced price, entailing a loss to the merchant or manufacturer.

My invention contemplates a simple and inexpensive protective device which may be made with a minimum of labor and material, which may be easily applied and secured to a wheel and may remain on the wheel when it is displayed for sale, providing an attractive finish which will protect and enhance the appearance of the article until the wheel is ready for use.

Various other advantages will suggest themselves to those acquainted in the art as the description proceeds.

Referring now to the drawings forming a part of the specification and illustrating certain preferred embodiments of my invention;

Fig. 1 is a perspective view showing a grinding wheel with a protective cover embodying my invention, a part being broken away for clearness;

Fig. 2 is a side elevational view, showing my improved protective device mounted on a wheel and secured somewhat differently from that of Fig. 1, with parts broken away;

Fig. 3 is a sectional view taken substantially on lines 3—3 of Fig. 2; and

Fig. 4 is an edge elevation of a wheel having secured thereto a protective device embodying my invention.

Numerals 10 indicates a grinding wheel or other disk to which devices embodying my invention may be applied. A cover comprising my invention, as seen best in Fig. 3, comprises a web indicated generally at 15 and having a main body portion 17 and reinforcing edge portions 20.

The edge portion 20 extends substantially at right angles to the main portion 17 so as to form a flange which overlaps the edge of the grinding wheel or like disk 10. On the inside, as indicated at 22, it will be seen that the cover conforms closely to the size and shape of the disk to be protected, and in the embodiment shown, the flange 20 provides a substantially rectangular shoulder.

2

The protective web may be readily formed by extrusion, or other suitable methods familiar to those skilled in the art, from a wide variety of suitable plastics of a chemical character which will provide the desired physical characteristics of toughness, flexibility and resistance to cracking, etc. Without any intention to limit myself, I might mention as examples of suitable material natural and synthetic rubber and combinations thereof and numerous plastic materials, such as vinyl acetate, polystyrene and other types having the characteristics indicated above. At any rate, the material is preferably formed in a continuous web and wound in spiral rolls for sale to the ultimate users thereof.

The protective web or cover may be applied or secured in various ways to a disk which it is desired to protect. In Fig. 1, I have shown the protective cover 15 cut to substantially the same circumferential length as the circumference of the disk 10 so that the web makes a butt joint as at 25, the ends of the web being secured together as by means of a short strip 27 of any suitable material overlying and secured to the ends of the web 15. The strip 27 might be heavy gummed paper, so-called "Scotch tape," or a film of any other suitable material bearing on one side a coating of adhesive by which it may be secured to the web 15, or it might be a strip of heat meltable plastic which might be welded to the web 15 by application of heat.

In Figs. 2 and 4, I have shown a different way of securing the web 15 to a disk. In this arrangement the web 15 is cut to such a length that the overhanging flanges 20 form a butt joint as at 25, but an integral portion of the body portion 18 is permitted to extend beyond said joint and to overlap as at 30 the other end of the web. Said overlap 30 may be secured to the adjacent body portion 18 by application of heat or of adhesive applied to the face of either portion.

No doubt other arrangements will suggest themselves to those skilled in the art and, hence, I do not intend to be limited to the specific forms shown and described herein.

I claim:

1. A protective cover for a disk of frangible material comprising a strip of flexible and yieldable material resistant to blows, said strip comprising a main web portion with integral side flanges extending substantially at right angles to the web portion, said web portion and side portion being sufficiently thick to offer substantial resistance against heavy blows, means for securing together the end portions of said strip, said strip being

formed of extruded plastic material and said flanges having a planar inner face, and said web portion extending beyond said flanges at one end of said strip in order that one end thereof may overlap and be secured to the opposite end thereof.

2. The combination of a frangible disk and a cover as defined in claim 1.

MILTON L. POUST.
